REMOTE CONTROL APPARATUS

John W. Luke, St. Augustine, Fla.

Application September 22, 1933, Serial No. 690,596

4 Claims. (Cl. 250—40)

This invention relates to methods and means for controlling from a remote position electric circuits and has particular application to the tuning of radio circuits.

5 The invention contemplates the provision of a control device readily accessible to the operator, said device including electro-responsive means whereby predetermined movement imparted to said device is transmitted to a distantly located 10 component part of a radio circuit for tuning the same.

The invention embraces the provision of means including a constantly operable electric motor and a plurality of driving elements associated 15 with electro-responsive means for transmitting rotary motion to a distantly located radio receiving set.

20 The invention has for an object the provision of a device embodying means to produce a relative movement between certain of the component parts of a radio circuit distantly placed from said device and obtaining the tuning of said radio circuit from a remote position.

25 The invention further comprehends the provisions of a circuit controlling means performing the dual function of actuating a component part of the radio circuit and energizing a remote control device.

30 Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawings of a form of the invention, which may be preferred, in which:

35 Figure 1 is an elevated view illustrating the apparatus of my invention associated with a radio set;

40 Figure 2 is a detailed perspective view of the control device of my invention with the outer casing being removed;

45 Figure 3 is a top plan view taken substantially on line 3—3 of Figure 2;

50 Figure 4 is a detailed view of the circuit control and manual switches shown in Figures 2 and 3;

55 Figure 5 is an enlarged detailed view taken substantially on line 5—5 of Figure 4;

Figure 6 is a view taken substantially on line 6—6 of Figure 4;

55 Figure 7 is a side elevational view of the circuit actuating device with the outer casing broken

away to show the electro-responsive means used for transmitting motion to one of the component parts of the radio set associated therewith;

Figure 8 is a view taken substantially on line 8—8 of Figure 7;

Figure 9 is a view taken substantially on line 9—9 of Figure 7;

Figure 10 is a view taken substantially on line 10—10 of Figure 7;

Figure 11 is a wiring diagram showing the 10 electric circuit used in my invention.

I have illustrated the device of my invention as used in connection with a radio set for the purpose of tuning the same, but it is to be understood that I do not wish to limit the construction or use of my device to the disclosure shown in the drawings and that I contemplate the use of the device wherever the same may be found to be applicable.

The principle of my invention is illustrated in the drawings and referring particularly to the embodiment shown in Figure 1 it comprises a control operating device 1 connected by means of a plurality of wires carried by a suitable cable 2 to a distantly located circuit actuating device 3, the latter being in close proximity to and interconnected with a radio receiving apparatus 4.

The control operating device 1 comprises an outer housing 5 through which projects a front plate 7 having a plurality of studs or spacing members 9 secured to back plate 10 as particularly illustrated in Figure 2. Fixedly supported on the rear face of plate 7 is a clock motor suitably enclosed in casing 12, the clock motor being provided with a dial 13 projecting through plate 7. The clock motor being in continuous motion not only serves as a time piece, but also drives shaft 14 which is journaled on back plate 10. Secured to shaft 14 by means of a set screw 15 is a driving gear 17, which is in driving engagement with gear 18, the latter being in mesh with gear 19. Gears 18 and 19 are loosely journaled on shafts 22 and 23 respectively. Gear 18 is provided with a circular metal plate or disc 24 preferably of magnetic material and gear 19 is also provided with a disc member 25 also of magnetic material. Fixedly mounted on shaft 22 is a frame 21 supporting an electro-responsive device or magnetic clutch consisting of electro-magnets 26 comprising energizing windings 28 and 30, the terminals of which are connected to suitable contacting rings 31 and 32 which are insulatingly carried by collar 29. Shaft 22 carries gear 33 shown in Figure 3 which is in engagement

with a pinion 35 fixed to shaft 36, the latter being journalled as at 38 on plate 7, and having a projection carrying a hand or pointer 40 which co-operates with a calibrated dial 41 mounted on plate 7. Pinion 35 is also in engagement with a gear 42 carried by shaft 23, the latter also serving to drive a frame upon which are secured contacting rings 43 and 44 to which are connected the terminals of windings 45 and 46 of the electro-responsive device or magnetic clutch of my invention. Coacting with contacting or slip ring 31 is a current carrying finger or contact member 48 insulatingly supported on bracket 49, the latter being fixed by any suitable means to back plate 10. Adjacent to contact arm 48 is a current conducting finger 51 coacting with ring 32 which is also insulatingly supported on bracket 49. Contact fingers 48 and 51 are normally flexed in order to provide good circuit connections with the corresponding contacting rings 31 and 32 and thereby permit the efficient energization of the windings 28 and 30. In order to establish a circuit for the proper energization of windings 45 and 46 contact fingers 53 and 54 are in engagement with contact rings 43 and 44 respectively.

For the purpose of selectively controlling the energization of the electro magnets, I have provided a plurality of manually operable switches, 30 in the embodiment illustrated the same being mounted on plate 7 and consisting of three independently actuated switching arrangements 55, 56 and 57. Switching arrangement 57 is manually controlled to cause the energization of the 35 windings of remote control clutches 116 and 117 located in the circuit actuating device 3 for adjusting the means which serve to determine the volume of the radio receiving set as hereinafter described; switching arrangement 56 in the embodiment illustrated is used for the purpose of 40 selectively energizing the windings 28-30 or 45-46 forming the magnetic clutch elements located in the control operating device 1 as well as the serially connected windings 118 of one clutch 45 element and serially connected windings 119 of another clutch element located in the circuit actuating device 3 which serve as means to establish a driving connection for moving the means 50 for tuning the radio receiving set as can be seen by examination of Figure 11, and switching arrangement 55 in the embodiment illustrated is for the purpose of aiding in the proper tuning of the radio circuit actuating device by selectively energizing the windings 28-30 or 45-46 forming 55 the clutch elements located in the control operating device 1 as well as the windings of clutch element 118 which are serially connected with windings 28-30 or the windings of the clutch element 119 which are serially connected 60 with windings 45-46. The diagram of connection of the switching arrangement to the source of power and clutch elements as well as the motor control is particularly illustrated in Figure 11. All of said switching arrangements are 65 similar in construction and for this reason it will be sufficient to only describe one in detail.

As is illustrated in Figure 2, switching unit 56 comprises a rod 60, removably secured to the front plate 7 which supports at its central position a retractive member or spring 61. Spring 61 is secured to the rod 60 by means of hooked member 62, as shown in Figure 2, the other end of spring 61 being secured to an anchor member 63 by means of another hooked member 64, the 70 anchor member 63 being secured to a shaft 66

by means of screw 65, as particularly shown in Figure 4. The tension caused by spring 61 serves to hold the shaft in its normal or neutral position. The shaft 66 is manually rotated by means of a knob or finger piece 74 shown in Figure 3. 5 Positioned on the shaft rearwardly of the front plate 7 is an arm 67. Spaced apart but adjacent thereto from the arm 67 are contact points 68 and 69, more clearly seen in Figure 5, contact points 68 and 69 also serving to support wires 10 76 and 76' respectively. Rotary movement of the knob 74 will throw the arm 67 in contact with either one of the contacts 68 and 69, depending on the direction in which the knob 74 is rotated. Positioned rearwardly of the arm 67 15 is a collar 71 supporting a pair of discs 72 and 73. As is shown in Figure 6, one of said discs 72 is mounted concentrically on the shaft 66 and is constructed of current conducting material supported on collar 71 of suitable material. The other of said discs 73 is mounted eccentrically on the shaft 66 and is constructed of insulating material. Wire 75 is secured, as by soldering, to the under side of disc 72. Riding on the discs 72 and 73 is a current conducting finger 77 removably 20 fixed to the front plate 7 by means of screw 78. Finger 77 also serves as a securing means for holding wire 79 in place.

The switching arrangement 56 hereinbefore described while controlling the electric motor 179 30 for driving the gear elements also controls the energization of the windings 28-30 or 45-46 of the electric magnetic clutches located in the control operating device 1 and the remotely located windings of magnetic clutches 118 and 35 located in the circuit actuating device 3, which are interconnected by suitable cable 2 carrying a plurality of wires. Cable 2 is removably connected to each of the devices through the use of connection plugs, and this arrangement permits that the control operating device and circuit actuating device can be located at any desired distance. The circuit actuating device 3 illustrated in Figure 7 comprises an outer casing 80, the front plate 81 and rear plate 82 of said 40 casing serving to journally support a plurality of shafts, 83, 83', 84 and 84'. Positioned forwardly of the rear plate 82 and freely mounted on their respective shafts are collars 88, 88', 89 and 89' carrying gears 93, 93', 94 and 94' each 45 of said gears being provided with a circular metal plate or disc 98, 98', 99, 99' preferably constructed of magnetic material. In front of said discs are collars 101, 102, 103 and 104 secured to their respective shafts by suitable means such as set 50 screws. Each of said collars carry frames 111, 112, 113 and 114 which in turn serve to support a pair of energized windings or coils 116, 117, 118 and 119 forming the remotely controlled magnetic clutches. Positioned forwardly of the second mentioned collars and mounted on their respective shafts by means of screws 120, 121, 122 and 123 is a third set of collars 125, 126, 127 and 128. Fixedly secured to each of said collars is a pair of contact or slip rings 130, 131, 132 and 65 133, each of said contact or slip rings having electrical connection with their respective energized windings or coils 116, 117, 118 and 119 by means of leads or wires 135, 136, 137 and 138. Removably secured to the forward end of their respective shafts are gears 150, 151, 152 and 153 supported by means of collars 140, 141, 142 and 143. It will be noted that gears 150 and 151 70 are in mesh with volume control gear 155, and gears 152 and 153 are in mesh with tuning con- 75

tral gear 156, the control gears being in driving relationship by means of shafts 157 and 158, respectively, with a component part of the radio set 4 for tuning the same. An enlarged detailed 5 illustration of the method employed to transmit current to the energized winding 116 is shown in Figure 8. The lead in wires 160 and 161 are secured to one side 162 of the casing 80 by the clamping means 164 and 165, also securing fingers 10 167 and 168 mounted interiorly of the casing 80, said fingers being in engagement with the current conducting contact or slip rings 130. Thus the lead wires 160 and 161 are connected to the leads 135 and to the energized windings 15 116. Figure 8 also further illustrates the manner in which the driving gear 170 rotated by means of a small electrical motor contained in the casing 171 is in mesh with gear 93 and serves to rotate said gear freely on the shaft 83. In conjunction with said motor is a speed reducing gear 20 case also contained in the casing 171.

The circuits of my invention are shown in Figure 11, wherein a source of electrical energy of 110 volts alternating current is connected by lead 25 175 to a transformer 176. Transformer 176 provides a current of low voltage for the purpose hereinafter described. The alternating current supply also serves to energize the continuously 30 rotating synchronous motor 177 (not specifically shown), and electric light bulb 178. Connected with the source of alternating current is the synchronous motor 179 which is independently energized or controlled by either of the switching arrangements 55, 56 or 57. The circuits from 35 the source of power to the synchronous motor 179 controlled by the switching arrangements 55, 56 and 57 are as follows: From one of the leads of the alternating current power lines 175 connected to binding post 201 located in the control operating device 1 to one of the terminals 203 of the synchronous motor 179 by means of conductor 204; from the other lead of the alternating current power lines 175 to binding post 206 hence by means of lead 75 to conducting 40 disk 72 of switch 55 adapted to engage the flexible finger 77 to close said circuit, from finger 77 by means of lead 79 to conductor 207 connected to lead 209 which in turn is connected with the other terminal 210 of the synchronous 45 motor, thus completing the energizing circuit controlled by switching arrangement 56. The energization of the synchronous motor from the source of power can also be established by a branch circuit controlled by switch 55, this branch 50 circuit comprising conductor 211 connected at one end to lead 75 and having its other end connected to the movable disk forming a component part of switch 55, which is adapted to contact with a flexible finger and hence from 55 the flexible finger by means of wire 214 to lead 209 which is connected to terminal 210 of the synchronous motor as hereinbefore described. The energization of the synchronous motor 179 is also controlled by a branch circuit including 60 switching arrangement 57, which comprises a conductor 215 connected at one end to lead 75, and its other end to the movable disk forming a component part of switching arrangement 57, which disk is adapted to contact with a flexible finger adjacent thereto and hence by means of 65 wire 216 to conductor 207 and from conductor 207 to lead 209 connected to the terminal 210 of the synchronous motor. Synchronous motor 179 is similar in construction and capable of 70 running at the same speed as motor 177. The 75

circuits so far described are indicated by heavy lines.

Transformer 176 is provided with a winding 180 for the purpose of producing a current of low voltage, serving to energize the windings of the 5 two sets of coupling or clutch coils 28, 30, 45 and 46 located in the control device 1 on the one hand, and the pairs of clutch coils 116, 117, 118 and 119 located in the circuit actuating device 3 on the other hand. In detail, the circuit is as follows: 10 One end of the low tension winding 180 of the transformer 176 is connected by means of lead 181 to the windings of clutch coils 119 from whence leads 188 and 192 which serves as circuit connecting means with control coils 45 and 46, 15 thence through lead 193 to contact terminal 68, which is capable of establishing contact with movable member 67 through shaft 66 and by means of lead 187 to the other end of the low tension winding 180 of transformer 176. Energization of control coils 45 and 46 and serially 20 connected coils 119 can also be obtained by the use of switching arrangement 55 by means of lead 187 connected to transformer winding 180 and to shaft 186 carrying movable terminal 184 25 capable of establishing contact with stationary contact 189 through lead 193 to coils 45 and 46 thence through leads 192 and 188 to coils 119 thence through lead 181 to other side of the 30 transformer winding 180.

The energization of clutch coils 118 is also obtained by means of lead 181, which connects with one end of winding of coils 118, hence through coil 118 and by means of lead 196 and 197, hence to coils 28, 30 connected in series, and back 35 through leads 185, 198 and 199 to stationary contact 69, cooperating with the contact or arm 67 of switch 56 through shaft 66 back through lead 187 to the low tension side of the coil 180 of the transformer 176. Coils 28, 30 as well as 40 coils 118 which are serially connected are also connected to switching arrangement 55 by means of leads 185, 198, 200 to stationary contact 182 for establishing a circuit connection through arm 184 and shaft 186 and lead 187 to the transformer 45 winding 180.

The volume control circuit is illustrated by control switch 57 at circuit 190 all connections illustrated, as connected and associated therewith. The action of the volume control is similar to that 50 just described in connection with the station control.

An equalizing switch 55 is in a circuit parallel with the control switch 56. My invention utilizes a separate manually operable control through the 55 equalizer switch 55, for obtaining an extremely fine adjustment.

The operation of my device is as follows: As was hereinbefore described the circuit actuating device is in close proximity to a radio receiver 4 60 and connected therewith by means of the volume control shaft 157 and tuning control shaft 158. The clock motor 177 contained in the control operating device 1 illustrated in the circuit diagram is in continual operation, not only serving as a 65 time piece but also driving shaft 14 and the gears associated therewith. The control operating device 1 being connected to the circuit actuating device 3 by means of the cable 2. Rotation or turning to the right or left switches 55, 56 or 57 70 by the operator using any of the manually operable finger pieces will start the electric motor 179 contained in the circuit actuating device 3 and will thru gear 170 start the rotation of the gear train illustrated in Figure 9. The specific 75

construction of the switches 55, 56, 57 allows an interval of time to permit the motor 179 to attain its maximum speed similar to motor 177. This construction is illustrated in Figure 6, of the drawings. Tuning control is affected as follows: Further manual rotation of the finger piece 74 will throw the arm 67 into contact with either one of the contact points 68 and 69 as illustrated in Figures 4 and 5, depending on the direction in which the knob 74 is rotated thereby closing the circuit and energizing either of the coil groups 118 or 119. Coil groups 118 being connected in series with group of coils 28 and 30 and group coils 119 being connected in series with group coils, 45 and 46 contained in the control operating device 1. As hereinbefore mentioned clock motor 177 drives gear train 17, 18, and 19 continuously. Gears 18 and 19 are loose rotating on shafts 22 and 23 but thru the energization of coils 28, 30 or 45 and 46, and the attraction of said coils to discs 24 and 25 hereinbefore described, motion is imparted to shafts 22 or 23 depending on which set of coils is energized, whereby the gears through the electromagnetic clutching action of the coils drive either of said shafts the energization of coils 28, 30 will establish a driving connection from gear 18 to shaft 22 driving gear 33 fixed thereto, which gear is enmeshed with pinion 35 fixed to the shaft 36 carrying pointer 40. The pointer hand positioning gears 42 and 33 meshing with pinion 35 on shaft 36 serve to drive the pointer 40 to a position on the calibrated dial 41 desired by the operator. A similar action takes place in the circuit actuating device 3 to position the radio tuning mechanism to a position as that shown by the pointer on dial 41. This being accomplished as follows: The manipulation of switch element 56 will first establish energization of synchronous motor 179 and will rotate the gear train located in the circuit actuating device 3 by means of gear 170 and also cause the energization of the clutch elements located in the circuit tuning device 3. For example, if the switch 56 is turned to a position to energize coils 28 and 30, the windings of clutch element 118 are simultaneously energized due to their series connection. The energization of the clutch element 118 will produce a magnetic clutch action and establish a driving connection between gear 94 and shaft 84 thereby rotating gear 152 fixed thereto and which is enmeshed with gear 153 fixed to shaft 158 which controls the adjustment of the tuning of the radio set.

The volume control switch 57 is in direct electrical relation with coils 116 and 117 and these coils combined with their associated mechanism produce a similar magnetic clutching effect to drive the shaft 157 thereby affecting the volume of radio receive 4.

The equalizing switch 55 provides an extremely fine adjustment for the tuning of radio receiver 4 by slightly increasing or decreasing the electrical energization imparted to the tuning coils 118 and 119 due to the amount of wire and the added resistance present in this circuit.

It is apparent that, within the scope of the invention modifications and different arrangements may be made other than is herein disclosed, and the present disclosure is illustrative merely, the invention comprehending all variations thereof.

What I claim is:

1. A remote control system for radio receiving sets having adjustable elements comprising a driven member operated to adjust one of said

elements; an electromagnet fixed to said driven member; a rotatable magnetizable member spaced from said electromagnets and adapted to drive said driven member through the action of said electromagnet; a constant speed motor for rotating said magnetizable member; a source of power and circuit connections between said source of power and said motor and electromagnet; a control device supporting a switch included in the circuit of said motor and in the circuit of said electromagnet for connecting the same to said source to energize the motor and the electromagnet for establishing a driving connection between said rotatable member and said driven member; an indicator in said control device; a driven element connected to said indicator; an electromagnet fixed to said driven element; and a constant speed rotatable member adjacent to said electromagnet, said switch also adapted to establish a driving connection between said second electromagnet and said rotatable member whereby the indicator shows the movement imparted to the adjustable element of the radio set.

2. A remote control system for radio receiving sets having adjustable elements comprising driven members operated to adjust said elements in one direction or the other; an electromagnet fixed to each of said driven members; a plurality of rotatable magnetizable members spaced from said electromagnets and adapted to drive said driven members through the action of said electromagnets; a motor for rotating said magnetizable members; a source of power and circuit connection between said source of power and said motor and electromagnets; a remotely located control device having switches included in the circuit of said motor and in the circuit of said electromagnets for selectively connecting the same to said source thereby energizing the motor and one of said electromagnets to establish a driving connection between a rotatable member and a driven member; an indicator in said control device; driven elements connected to said indicator for moving the same; electromagnets fixed to said driven elements and being connected in series with one of said first mentioned electromagnets; rotatable members adjacent to said electromagnet, said switches also adapted to establish a driving connection between said second electromagnet and said rotatable member whereby the indicator shows the movement imparted to the adjustable elements of the radio set.

3. A remote control system for radio receiving sets having adjustable elements comprising driven members connected to said elements and operated to move the same; and electromagnet fixed to each of said driven members; a plurality of rotatable magnetizable members spaced from said electromagnets and adapted to drive said driven members through the action of said electromagnets; a motor for rotating said magnetizable members; a source of power; electrical conductors for establishing a circuit for the flow of current from said source of power to said motor and to said electromagnets; a remotely located control device including an indicator; driven elements connected to said indicator for moving the same; electromagnets fixed to said driven elements, and being connected in series with one of said first mentioned electromagnets; rotatable members adjacent to said last mentioned electromagnets; a plurality of switches adapted to connect the first and last mentioned electromagnets and said motor with said source of power to establish a driving connection between said electro-

magnets and the corresponding rotatable members to adjust said radio set and move said indicator to show the movement imparted to the adjustable elements of the radio set.

5 4. A remote control system for radio receiving sets having adjustable elements comprising driven members connected to said elements and operated to move the same; an electromagnet fixed to each of said driven members; a plurality 10 of rotatable magnetizable members spaced from said electromagnets and adapted to drive said driven members through the action of said electromagnets; a motor for rotating said magnetizable members; a source of power; electrical conductors for establishing a circuit for the flow of current from said source of power to said motor and to said electromagnets; a remotely located control device having switches included in the circuit of said motor and in the circuit of said

electromagnets for selectively connecting the same to said source to energize the motor and one of said electromagnets for establishing a driving connection between a rotatable member and a driven member; an indicator in said control device; driven elements connected to said indicator for moving the same; electromagnets fixed to said driven elements, and being connected in series with one of said first mentioned electromagnets; rotatable members adjacent to said 15 electromagnets, said switches also adapted to connect said last mentioned electromagnets with said source to establish a driving connection between said second electromagnets and said rotatable member whereby the indicator shows the 15 movement imparted to the adjustable elements of the radio set.

JOHN W. LUKE.
